UNITED STATES PATENT OFFICE.

DAVID W. BOWE, OF TOLEDO, OHIO.

FENCE-TOOL.

1,175,228.

Specification of Letters Patent. Patented Mar. 14, 1916.

Application filed April 8, 1915. Serial No. 20,001.

To all whom it may concern:

Be it known that I, DAVID W. BOWE, a citizen of the United States, residing at Toledo, in the county of Lucas and State of Ohio, have invented a new and useful Fence-Tool, of which the following is a specification.

This invention relates to fence tools and more particularly to a device for use in fastening the wires of a fence to concrete posts and the like.

One of the objects of the invention is to provide a tool having means for engaging a fence wire adjacent opposed sides of a post, means being provided whereby the wire can be drawn back so as to partly lap the sides of the post where it will be held until a clip has been applied to the post and wire.

20 A further object is to provide an instrument of this character which will lock automatically when the wire has been drawn against the post so that both hands of the user are thus left free to place a clip about the post and in engagement with the wire.

25 Another object is to provide a device of this character adapted for use in connection with posts of different sizes and which has spacing means whereby a clip can be readily inserted between the post and the wire engaging elements.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 35 within the scope of what is claimed, without departing from the spirit of the invention.

In the accompanying drawings the preferred form of the invention has been shown.

40 In said drawings:—Figure 1 is a plan view of the device in the first position assumed thereby while being applied to a fence post and wire. Fig. 2 is a similar view showing the top plate of the tool re-45 moved and the parts locked in position, a clip being shown in engagement with the wire and post. Fig. 3 is a section on line A—B, Fig. 1.

45 Referring to the figures by characters of reference 1 designates the body of the device, the same being provided at one end

with outwardly diverging arms 2 and 3, the body being open between said arms and also at the opposite end thereof. The inner faces of the side walls of the body diverge 50 away from the arms and the space within the body is designed to receive a head 4 adapted to slide within the body. This head has a stem 5 projecting from one end thereof and pivotally connected to the head 65 at opposite sides thereof are links 6. These links are in turn pivotally connected to segmental heads 7 provided upon levers 8 which are fulcrumed, as at 9, within the body 1. The heads 7 have recesses 10 in which the 70 links are mounted so that the upper faces of the links and the heads 7 are disposed in substantially the same plane. Recesses 11 are also preferably formed in the head 4 for the reception of the adjacent ends of links 75 6. A cover plate 12 is secured upon the body 1 and serves to house the links 6 and to hold the head 4 and levers 8 against displacement relative to the body 1. By referring to Fig. 2 it will be seen that the segmental heads 7 extend close to the sides of the stem 5 so as thus to hold said stem and the head 4 against lateral swinging within the body. The long arms of levers 8 constitute handles and can be of any desired 80 construction.

Extending from one side of the body 1 is an ear 13 in which is mounted a stop screw 14 designed to be engaged by the adjacent lever 8 so as thus to limit the outward 90 swinging movement of the two levers.

The arm 2 is provided, in its upper face, with spaced notches 15 and, along its inner side, with a longitudinal spacing flange 16. The arm 3, which is comparatively short, is 95 pivotally engaged by another arm 17 having notches 18 similar to the notches 15 and also having a longitudinal spacing flange 19. A stop lug 20 extends from the arm 3 and projects into a short groove 21 in the arm 17 thus to limit the swinging movement of said arm 17 relative to the arm 3. A spring 22 extends from the arm 3 and bears against arm 17 so as to hold it normally pressed inwardly toward the arm 2. 100 105

In using the device herein described, the arms 2 and 17 are placed astride a fence post P and one of the notches in each of said arms is arranged to receive the fence wire W which is to be secured. With the parts 110 thus positioned, the operator swings the levers 8 toward each other so that the points

of connection between the segmental heads 7 and the links 6 are moved past their dead centers, thus to hold the head 4 against return movement after being thrust out-
wardly from the body 1. This thrusting action which is exerted against the head 4 through the links 6 results in pulling the arms 2 and 17 back so as to crimp the wire W at the sides of the post. The parts will 10 be held in these positions by the levers 8 which assume the positions shown in Fig. 2 and, consequently, the device can be released and will remain clamped against the post. The operator can then place a clip upon 15 the post and in engagement with the wire so as to hold the wire bound tightly against the post after the tool has been removed. The clip used preferably consists of a bowed wire 23 so shaped as to be easily placed 20 astride the post, the terminals of the wire being bent into hooks adapted to engage the wire. It is to be understood that should the arms 2 and 17 fit close to opposed portions of the post, the flanges 16 and 19 25 would hold them spaced sufficiently from the post to permit the ready insertion of the clip between the post and the arms. By pivotally mounting arm 17 the tool can be adapted for use in connection with posts of 30 different sizes.

What is claimed is:—

1. A device of the class described, including a body, spaced wire-engaging members carried thereby, a post-engaging head slidably mounted within the body, actuating levers pivotally connected to the body, and links connecting said levers to the head, the connecting points between the links and head being shiftable past the dead centers 35 to lock the slidable head when projected from the body.
2. A device of the class described, including a body, spaced wire-engaging members carried thereby, a post-engaging head slidably mounted within the body, levers fulcrumed within the body and having heads at one end, links pivotally connected to said 40
- 45

heads and to the slidable head, said levers and links being shiftable to project the head from the body and to hold said head in projected position. 50

3. A device of the class described, including a body, spaced fixed and pivoted wire-engaging arms carried thereby, a spacing member carried by each arm, yielding means 55 for holding the pivoted arm normally in a predetermined position relative to the fixed arm, a post-engaging head slidably mounted in the body, and means for projecting said head into the space between the arms. 60

4. A device of the class described, including a body, spaced fixed and pivoted wire-engaging arms carried thereby, yielding means for holding the pivoted arm normally in a predetermined position relative to the fixed arm, coöperating means upon 65 the pivoted arm and the body for limiting the pivotal movement of said arm, a post-engaging head slidably mounted relative to the body, and means for projecting the head 70 into the space between the arms.

5. A device of the class described, including a body, spaced fixed and pivoted wire-engaging arms carried thereby, a longitudinally extending spacing member upon the 75 inner side of each arm, yielding means for holding the pivoted arm normally pressed toward the fixed arm, means for limiting the pivotal movement of the pivoted arm, a post-engaging head slidably mounted in the 80 body, levers fulcrumed in the body, link connections between said levers and the head, and means for limiting the movement of the levers from each other, said levers and links coöperating to hold the head in projected position. 85

In testimony that I claim the foregoing as my own, I have hereto affixed my signature in the presence of two witnesses.

DAVID W. BOWE.
